SEPARABLE CONNECTOR

Julian Rogoff, New Rochelle, N. Y.

Application October 24, 1942, Serial No. 463,179

2 Claims. (Cl. 287—103)

My invention relates to separable electrical connectors.

It is customary in aircraft wiring to use terminal strips with threaded studs mounted thereon to make connections between wire ends to which wire terminals have been attached. Such terminal strips are bulky, relatively heavy, and require boxes or enclosures to prevent accidental short circuits. An object of my invention is to provide a slit connector which is small and easily covered by means of insulating tubing or "spaghetti." A further object is to provide such a connector which can be installed directly in the wiring at any desirable point.

Modern airplane construction provides for the assembly of "sub-assemblies." For example, wing sections or tail sections are attached to the fuselage, usually in separable fashion, so that when these parts are damaged they may be readily replaced. I have found that, under such circumstances, the electrical wiring between the separable parts should be readily detachable. The use of permanent splices in the wire at these points is, I have found, both inconvenient and wasteful of time. I have additionally found that the separable connectors in the wiring at these points should be such that they will separate at a definite tensile pull, usually about 10 or 12 pounds. Thus, in case of accident, the wires will separate at predetermined joints and damage of wiring and of delicate instruments by pulling or shock will be avoided.

The primary object of my invention, therefore, is to provide a separable connector which will separate at a predetermined value, in a longitudinally applied tensile pull.

A further object of my invention is to provide a connector to which the wires may be attached with or without the use of solder, as desired.

Another object of my invention is to provide a separable connector which can be manufactured by high speed production methods with a minimum of scrap or material waste.

I accomplish these and other objects and obtain my new results as will be apparent from the device described in the following specification, particularly pointed out in the claims, and illustrated in the accompanying drawing, in which:

Fig. 1 illustrates a plan view of one part of my separable connector attached to a conductor.

Fig. 2 is a sectional view thereof taken along the line 2—2 of Fig. 1.

Fig. 3 is an end view of the part.

Fig. 4 is a side elevation of the same.

Fig. 5 illustrates two identical parts assembled together.

Fig. 6 is a longitudinal cross-sectional view of the same.

Fig. 7 illustrates a modified form of engaging means for holding the two parts together.

Referring more particularly to the drawing, my separable connector consists of two halves or portions 10 and 10a, as illustrated in Fig. 5, which are interlocked together. One of these halves 10, is illustrated in Figs. 1 to 4. It consists of a tubular body 11, formed at one end with an enlarged head 12, split as at 13, to receive and by compression to hold the insulation 14 of the conductor 15, and at the other end thereof, two extending fingers 16 and 17 formed by the longitudinal slot 18.

The extending fingers 16 and 17 are semi-cylindrical in cross-section, as indicated in Fig. 2, with the finger 16 having a radius of curvature on its outside surface 19 substantially equal to the radius of curvature of the inside surface 20 of finger 17, so that when the two sets of fingers of each half 10 and 10a are interlocked together, they will slidably and tightly accommodate each other as shown in Fig. 6.

The end of fingers 16 and 17 are provided with inwardly bent tabs 21 and 22 at the free ends thereof. An aperture 23 is formed in finger 16 at a point away from the free end for interlocking the two halves, as will be hereinafter explained.

A small indentation 24 may be formed adjacent the neck 11 of the half 10, so that the inner projection thereof 25 on the surface 20 may be used as a stop for the conductor 15 inserted into the bore 26 of the tubular body 11.

The conductor 15 may be soldered in the bore of the tubular body 11 or it may be secured therein by the indentation 27.

In Figs. 5 and 6, where the two identical halves 10 and 10a are shown assembled together, various parts on 10a, corresponding to 10 are correspondingly numbered with an "a" placed after each number.

It will be noted that tab 21a of portion 10a is sprung into aperture 23 of portion 10, the finger 17a providing a spring effect on the tab so as to maintain it in the aperture under spring pressure. The tabs 22 and 22a of fingers 16 and 16a ride in the inner surface of fingers 16a and 16 respectively, and act as a guide to prevent improper assembly of the two halves 10 and 10a.

I have thus provided a separable connector consisting of two identical parts, each provided with extending fingers so disposed that they will inter

lock with the extending fingers of the other part; the inner fingers forming a complete cylinder when interlocked, and the outer fingers providing spring pressure on the inner fingers to keep the latter in close electrical and mechanical contact. The tabs 21 and 21a act as catches and the amount of tension required to separate the two parts can be controlled by adjusting this tab.

Various methods of interlocking the two halves may be provided, an additional example being illustrated in Fig. 7, where the fingers 16 and 16a at the free end thereof may each be provided with a tit 30 and 30a respectively, which snap into apertures 31 and 31a, which may be positioned in finger 17 opposite the tit, when assembled thereto.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments herein shown and described are only some of the many that can be employed to attain these objects and

What I claim and desire to secure by Letters Patent, is as follows:

- 5 1. A connector for separably splicing two conductors together, consisting of two tubular body sections, each identically provided with a pair of integrally extending fingers, one of said fingers of each pair having locking means adapted to cooperate with complementary locking means carried by the other body section, for locking the two body sections together, said locking means releasable from the complementary locking means for releasing the two body sections from each other upon the application of a predetermined longitudinally applied tensile force.
- 10 2. A connector for separably splicing two conductors together, consisting of two tubular body sections, each provided with a pair of integrally extending fingers, one of said fingers of each pair having locking means adapted to cooperate with complementary locking means carried by the other body section, for locking the two body sections together, the other of said fingers constituting an alignment means to guide the two body sections into proper locking position, said locking means releasable from the complementary locking means for releasing the two body sections from each other upon the application of a predetermined longitudinally applied tensile force.
